CLAIM

The ornamental design for an air filter for a hot air hand device, as shown and described.

DESCRIPTION

FIG. 1 is a top plan view of the air filter for a hot air hand device showing our new design;

FIG. 2 is a bottom plan view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a front perspective view thereof;

FIG. 8 is a front perspective view thereof shown mounted onto a hot air hand device;

FIG. 9 is a top plan view of a second embodiment of the air filter;

FIG. 10 is a bottom plan view thereof;

FIG. 11 is a front elevational view thereof;

FIG. 12 is a rear elevational view thereof;

FIG. 13 is a right side elevational view thereof;

FIG. 14 is a left side elevational view thereof;

FIG. 15 is a front perspective view thereof; and,

FIG. 16 is a front perspective view thereof shown mounted onto a hot air hand device.

The features shown in broken lines depict environmental subject matter only and form no part of the claimed design.
